UNITED STATES PATENT OFFICE.

CHRISTOPHER SAMUEL DAVY, OF DULWICH, LONDON, ENGLAND, ASSIGNOR TO THE BABCOCK & WILCOX COMPANY, OF BAYONNE, NEW JERSEY, A CORPORATION OF NEW JERSEY.

MECHANICAL STOKER.

1,200,088.

Specification of Letters Patent.

Patented Oct. 3, 1916.

Application filed October 10, 1914. Serial No. 866,039.

To all whom it may concern:

Be it known that I, CHRISTOPHER S. DAVY, a subject of the King of Great Britain, residing at Dulwich, London, England, have 5 invented certain new and useful Improvements in Mechanical Stokers, of which the following is a specification.

This invention relates to mechanical stokers presenting an inclined grate surface and 10 adapted to be fitted to the furnaces of steam generators and the like.

The invention contemplates an improved construction of stoker wherein the fuel is forced to travel down the inclined grate 15 surface by the sliding and pushing action of rows of grate elements or bars pivotally supported on bearers or bars which extend transversely of the furnace, and made so as to be capable of being easily lifted out and 20 replaced without dismounting any other part.

According to the invention the elements or bars forming the grate surface, which are of comparatively short length, and are 25 placed side by side, are each formed at one end with a jaw so designed as to permit of the grate bar dropping over the transverse bearer therefor and to pivot thereon; each alternate transverse bearer being supported 30 on a rocking frame actuated by an eccentric or by cams fixed on a revolving transverse shaft, or by other suitable means, and the intermediate transverse bearers being fixed in a frame at the sides of the furnace. By 35 the rocking or reciprocating motion of said frame, and consequent movement of the grate bars, the fuel is pushed forward and down the bars at the same moment as the inclination of the bars is changed, a continuous 40 variation of the thickness of the bed of fuel being thereby produced.

The invention is illustrated by way of example in the accompanying drawing which represents a longitudinal section through a 45 furnace equipped with a mechanical stoker embodying the features above referred to.

Referring to the drawing, the grate surface is formed by rows of grate elements or bars 1 and 1' each of which bars is provided at one end with a jaw 2 which drops over the bulbous head of one of the transverse bearers or bars 3 and 4, and rests at the opposite end upon a grate element of

the row next beneath. The bearers 3 are fixed to the frame members 5, and the bearers 4 to the frame members 6. Each frame member 5 is pivoted on the shaft 7 at one end, the other end having fixed to it a quadrant 8 meshing with a toothed pinion 9 operated by the worm wheel 10 and worm 11 on shaft 11'. The frame 5 is thus adjustable to permit the grate to be set at any desired inclination to suit the class of fuel used. Loose flanged pieces 12 may be fitted on the frame member 5 to allow for expansion in the furnace, and to prevent ingress of air between the furnace walls and the grate.

At the lower end of the frame 5 is fitted a pivot shaft 13, upon which the lower end 70 of each frame member 6 rests. The upper end of each frame member 6 is supported and receives a rocking motion by attachment to a link 14 operated by a lever 15 fixed to the shaft 7. The lever 15 is actuated by 75 a lever 16, also fast on shaft 7, and to which is connected the rod of an eccentric 17 on the shaft 18. The lever 16 is provided with a series of openings 16' so that the movements of the grate bars may be graduated 80 by altering the position of the pin at the end of the eccentric rod on the lever 16.

Owing to the rocking motion of the frame members 6 sustaining the movable bearers 4, curvilinear movements are imparted to 85 the grate elements or bars 1' pivotally supported by said movable bearers. The magnitude of the curvilinear movements of the grate bars forming a separate row differs from that of the movements of the grate 90 bars forming an adjacent row on account of the different relationship of the corresponding bearers and the pivot shaft 13.

On the shaft 7 are mounted levers 19 which carry a transverse bearer 20, upon 95 which are dropped pivoted push bars 21 disposed beneath the outlet orifice of the feed hopper 22 and receiving reciprocatory movements to insure that fuel from the hopper will be supplied to the grate. The push 100 bars 21 are actuated by an adjustable connecting link 23 between the levers 19 and 15, or by other suitable mechanism.

The fuel is fed on to the grate from the hopper 22 by the push bars 21 and is agitated and pushed down the inclined grate 105

surface by the action of the alternate rows of movable grate bars, the thickness of the fire being adapted to be graduated by raising or lowering the furnace door 24.

5 The furnace may be arranged for either forced or natural draft. When forced draft is used, the front doors 25 are closed, air under pressure being admitted into the ash-pit. When the furnace is worked under 10 natural draft the doors 25 are left open.

What I claim and desire to secure by Letters Patent of the United States is:—

1. A mechanical stoker having an inclined grate surface formed by a plurality of transverse rows of grate elements, a pivoted frame in which alternate rows of said elements are supported, means for rocking said frame, and a stationary frame on which the intermediate rows of said elements are supported.

2. A mechanical stoker having an inclined grate surface formed by a plurality of transverse rows of grate elements, a pivoted frame in which alternate rows of said elements are pivotally supported, means for rocking said frame, and a stationary frame on which the intermediate rows of said elements are supported.

3. A mechanical stoker having an inclined grate surface formed by a plurality of transverse rows of grate elements, a pivoted frame on which alternate rows of said elements are supported, means for rocking said pivoted frame, and a stationary frame on which the intermediate rows of said elements are pivotally supported.

4. A mechanical stoker having an inclined grate surface formed by a plurality of transverse rows of grate elements, a pivoted frame in which alternate rows of said elements are supported, means for rocking said frame, a stationary frame in which the intermediate rows are pivotally supported, and means for adjusting the inclination of said frames.

45 5. A mechanical stoker having an inclined grate surface formed by a plurality of transverse rows of grate elements, a frame in which alternate rows of said elements are pivotally supported, a second frame in 50 which the intermediate rows are pivotally supported, and a pivot carried by the last-named frame upon which the first-named frame is supported.

55 6. A mechanical stoker having an inclined grate surface formed by a plurality of transverse rows of grate elements, a frame on which alternate rows of said elements are pivotally supported, and a frame on which the intermediate rows are pivotally supported, said first-named frame being pivoted 60 upon the other frame.

65 7. A mechanical stoker having an inclined grate surface formed by a plurality of transverse rows of grate elements, a pivoted frame on which alternate rows of said elements are

pivotedly supported, means adjacent one end of said frame for rocking it upon its pivot, and a stationary frame upon which the intermediate rows of said elements are pivotally supported.

8. A mechanical stoker having an inclined grate surface formed by a plurality of transverse rows of grate elements, a pivoted frame on which some of said elements are supported, and a stationary frame on which the remainder of said elements are pivotally supported, and means for rocking the pivotally supported frame.

9. A mechanical stoker having an inclined grate surface formed by a plurality of transverse rows of grate elements, a pivoted frame carrying bearers upon which alternate rows of said elements are pivotally supported, a stationary frame also carrying bearers upon which the intermediate rows of said elements are pivotally supported, the elements of the intermediate rows resting at their outer ends upon the grate elements of the row next beneath, and means for rocking said pivoted frame.

10. A mechanical stoker having an inclined grate surface formed by a plurality of transverse rows of grate elements, a pivoted frame on which alternate rows of said elements are pivotally supported, means for rocking said frame, a second pivoted frame on which the intermediate rows of said elements are supported, said last-named frame carrying the support upon which the first-named frame is pivoted, and means for varying the angle of inclination of the grate surface.

11. A mechanical stoker having an inclined grate surface formed by a plurality of transverse rows of grate elements, two frames in which said elements are pivotally supported, and means for producing a relative rocking movement between the frames.

12. A mechanical stoker having an inclined grate surface formed by a plurality of transverse rows of grate elements, a frame in which alternate rows of said elements are pivotally supported, a second frame in which the intermediate elements are pivotally supported, and means for producing a relative rocking movement between said frames.

13. A mechanical stoker having an inclined grate surface formed by a plurality of transverse rows of grate elements, a pivoted frame carrying bearers having bulbous heads on which alternate rows of said elements are pivoted, a stationary frame carrying bearers also having bulbous heads on which the intermediate rows of said elements are pivoted, and means for rocking said pivoted frame.

14. A mechanical stoker having an inclined grate surface formed by transverse rows of grate elements, two frames one of which is pivotally supported upon the other,

one of said frames carrying some of said elements and the other frame the remainder of said elements, and a support for both of said frames about which their lower ends 5 may be raised or lowered to vary the inclination of the grate surface.

In testimony whereof I have hereunto

signed my name in the presence of two subscribing witnesses.
